UNITED STATES PATENT OFFICE.

CHARLES N. MCFARLAND, OF KINGSTON, PENNSYLVANIA, ASSIGNOR TO THE ADDER MACHINE COMPANY, OF KINGSTON, PENNSYLVANIA, A CORPORATION OF PENNSYLVANIA.

ELIMINATING-KEY FOR ADDING-MACHINES.

1,024,013.

Specification of Letters Patent. Patented Apr. 23, 1912.

Application filed September 20, 1906. Serial No. 335,357.

To all whom it may concern:

Be it known that I, CHARLES N. MCFARLAND, a citizen of the United States, residing at Kingston, in the county of Luzerne 5 and State of Pennsylvania, have invented certain new and useful Improvements in Eliminating-Keys for Adding-Machines, of which the following is a specification.

My invention relates to adding machines and its object is to provide means entirely under the control of the operator whereby the mechanism for accumulating the items to be added and recorded may be utilized to record a number without accumulating it 15 into the total of the other items enumerated. Machines of this class have reached a high degree of perfection and are accurate and reliable. They commonly comprise registering mechanism, accumulating and recording or printing mechanism, and the usual operation is to set up the items on keys, and then by the movement of a handle or the vibration of a shaft, set in motion trains of mechanism whereby the items so set up are 20 recorded and accumulated and finally through other mechanism, a total is determined and recorded. There are a variety of other functions performed by the different mechanisms, but the above is their main 25 purpose. It is convenient at times to print in connection with the items enumerated a number, designating for instance the number of a check or its date. I have provided improved means called an "eliminating 30 key" or non-adding key whereby the function of the accumulating mechanism is interrupted without effecting the functions of the other mechanism. I also provide means for restoring this function or keeping it interrupted at will.

In order to explain the invention I shall describe it in connection with the related parts of an adding machine and I have selected for that purpose the machine which 45 is the subject matter of Letters Patent No. 777,032 issued Aug. 15, 1905 and No. 794,205, issued July 11, 1905, to Charles Wales and refer to those patents for a particular description of the mechanism not directly involved here.

In the drawing there is shown in Figure 1 a side elevation and partial vertical section of that portion of an adding machine embodying my invention. Fig. 2 is a similar view illustrating some of the parts shown

in Fig. 1 and other parts, including the keys and connecting mechanism. Fig. 3 is a detail transverse sectional view, broken out in the middle, showing the numeral wheels in elevation.

The registering mechanism consists of a bank of keys arranged in denominational series, as at 80, each key provided with a stem 81 by the depression of which a stop, 85 as at 82 corresponding to the numeral value of the key depressed, is interposed in the path of rack bars as described in the Wales patents above referred to.

In the drawing the rack bars are designated 20. These are each provided with toothed racks 21 on their upper edges and are supported at their front ends upon links 22 suitably pivoted, and at their rear ends upon the extremities of bell crank levers 23 mounted to oscillate upon a shaft 24. The 70 other ends of the bell cranks are pivotally connected to the printing mechanism. The rack bars 20 are adapted to mesh with pinions 30 with which the numeral wheels 31 are provided. These numeral wheels display the digits in proper order on their edges, (not shown) and are all mounted on a common shaft 32, there being one wheel for each denominational series of keys. It is readily seen that when the rack bars 20 85 are moved forward, and the racks are in mesh with the pinions 30, that the extent of rotation of the wheels is determined by the extent of the movement of the racks, which in turn is governed by the position of the 90 stops above referred to and which is permanently controlled by a series of permanent stops provided for that purpose one of which is seen at 25.

A main shaft 40 is adapted to vibrate 95 either by a handle manually operated or from a suitable source of power. This oscillates a sector 41 provided with a leg 42 which in turn, through a pin 43, moves a train of mechanism whereby the racks 20 100 are moved and through them movement is communicated to the printing mechanism. This latter comprises a series of type bars 50 arranged in vertical order on a carrier 51 so that, when a rack is moved, its type bar is raised until the type carrying the number corresponding to the extent of its movement is opposite the point of print. This point of print is in a fixed horizontal plane and is opposite the shaft 52 of the 110

platens 53 which in turn is mounted upon a carriage 54 adapted to move laterally in the machine. It will be understood of course that suitable means are provided to ink the type and propel forward the paper and to move the parts in harmony to perform their functions.

The accumulating mechanism is not shown complete in the drawing. It is fully described in the patents of Wales referred to. It comprises carrying mechanism whereby when a number greater than 9 is accumulated on one numeral wheel it is suitably transferred to the wheel of next higher designation and zero restoring mechanism, whereby the parts are all replaced in their initial position when the adding operation has taken place.

All of the parts so far described form no part specifically of my invention.

At each side of the frame work of the machine, at a convenient place, a lever 60 is pivoted on a shaft or pivot 61. They are of the bell crank type. One arm 62 is hinged 25 to a stem 63 of a key 64 provided with a finger piece 65 projecting above the case of the machine. Another arm 66 is provided at its lower extremity with a hook or projection 67 adapted to swing under the numeral wheel shaft 32 to support it. A spring 68 serves normally to pull the arm 66 away from the numeral wheel shaft. The key stem 63 is provided with a fin 69 adapted to engage with the under side of the plate 70 apertured at 71 to permit of the passage of the key stem, 63 and which plate is secured to the frame of the machine by screws 72, 73 or in some other suitable manner. Now it must be remembered that no accumulation 40 of an item registered by the key will take place unless the numeral wheels are rotated. This rotation, as has been seen, is accomplished by the engagement of the rack bars 20 with the pinions 30. It is obvious, however, that even if these rack bars 20 do not engage with these pinions, when an item has been set on the keys and the main shaft 40 is oscillated, that all other parts will perform their functions. The rack bars will 50 swing to an extent determined by the position of the stops limiting their movements and the item enumerated will be printed upon the roll or platen, but the item will not be accumulated. The engagement between the rack bars and the numeral wheel pinions I prevent by depressing the key 64. This 55 swings the bell crank lever 60 until the hook 67 comes beneath the shaft 32. So long as this condition exists, the numeral wheel pinion cannot engage with the rack bars. I may lock the key in this position by pressing the fin or shoulder 69 beneath the edge of the plate 70 and so long as it stays locked, the items enumerated are registered and 60 printed but not accumulated. The key is

released simply by moving it so that the fin 69 is removed from beneath the edge of the plate 70 when the spring 68 retracts it to position and the hook 67 is moved away from the numeral wheel shaft and no longer supports it and thereafter the items registered are accumulated until the key 64 is again manipulated. I call this key an "eliminating" or "non-adding" key because it temporarily eliminates or interrupts the function 75 of the accumulating mechanism, and when depressed the accumulating mechanism cannot add.

What I claim as new is:

1. In a machine of the class described, comprising racks, numeral wheels, each provided with a pinion adapted to engage a rack, and a depressible eliminating key, adapted by its depression directly to hold the pinions out of engagement with their respective racks.

2. In a machine of the class described, comprising racks, numeral wheels, each provided with a pinion adapted to engage a rack, a depressible eliminating key adapted by its depression directly to hold the pinions out of engagement with their respective racks, and means for elevating said key to permit the pinions to be lowered into engagement.

3. In a machine of the class described, comprising racks, numeral wheels, each provided with a pinion adapted to engage a rack, a depressible eliminating key adapted by its depression directly to hold the pinions out of engagement with their respective racks, and means for holding said key depressed.

4. In a machine of the class described, comprising racks, numeral wheels, each provided with a pinion adapted to engage a rack, a depressible eliminating key, adapted by its depression directly to hold the pinions out of engagement with their respective racks, and means for holding the key depressed or elevated at will.

5. In a machine of the class described, comprising racks, numeral wheels, each provided with a pinion adapted to engage a rack, the combination therewith of means adapted directly to hold the pinions out of engagement with racks, and a depressible key attached to said means.

6. In a machine of the class described, comprising racks, numeral wheels, each provided with a pinion adapted to engage a rack but normally out of engagement therewith, a key, and a hook operated thereby and which is adapted to engage the numeral wheel shaft and hold the numeral wheels 12 out of engagement with their racks, when the key is held depressed.

7. In an adding machine comprising numeral wheels provided with pinions, racks by which they are moved, a main shaft, 13

- means adapted to move the racks therefrom, means normally keeping the pinions out of engagement with the racks during the forward stroke of the shaft and in such engagement during the rearward stroke of the same shaft, a key, in combination with means connected to the key whereby the pinions are restrained from such engagement during the entire stroke of the main shaft.
8. In an adding machine comprising numeral wheels provided with pinions, racks by which they are moved, a main shaft, means adapted to move the racks therefrom, means normally keeping the pinions out of engagement with the racks during the forward stroke of the shaft and in such engagement during the rearward stroke of the same shaft, in combination with means operated from a key whereby the pinions are restrained from such engagement during the entire stroke of the main shaft consisting of a frame, levers rocked therefrom and hooks on the levers adapted to be moved into position to prevent the movement of the pinions.
9. In an adding machine, numeral wheels arranged in denominational series, a common shaft on which they are all mounted, pinions one adjacent to each wheel on the common shaft, a series of racks arranged beneath the pinions, means adapted to move the shaft downward to bring the pinions into engagement with their racks, a key, and means operated by the key adapted directly to prevent such engagement.
10. In an adding machine, numeral wheels arranged in denominational series, a common shaft on which they are all mounted, pinions one adjacent to each wheel on the common shaft, a series of racks arranged beneath the pinions, means adapted to move the shaft downward to bring the pinions into engagement with their racks, and means operated by a key adapted to prevent such engagement comprising an oscillating frame moved from the key and devices thereon adapted to be moved therefrom into the downward path of the shaft to intercept its movement.
11. In an adding machine, numeral wheels arranged in denominational series, a common shaft on which they are mounted, pinions one adjacent to each wheel on the common shaft, a series of racks arranged beneath the pinions, means adapted to move the shaft downward to bring the pinions into engagement with their racks, and means operated by a key adapted to prevent such engagement comprising an oscillating frame moved from the key and a plurality of levers moved therefrom each provided with a hook adapted to move beneath the shaft when the key is depressed.
12. In an adding machine, comprising numeral wheels provided with pinions, arms swinging on pivots, racks carried by said arms and adapted to engage the pinions, a main shaft, means adapted to move the racks therefrom, means normally keeping the pinions out of engagement with the racks during the forward stroke of the shaft and moved into such engagement during the rearward stroke of the same shaft, in combination with means operated from a key whereby the pinions are restrained from such engagement during the entire stroke of the main shaft.
13. In an adding machine, comprising numeral wheels provided with pinions, racks by which they are moved, an extension on one of said swinging arms, a printing mechanism operated by said extension, a main shaft, means adapted to move the racks therefrom, means normally keeping the pinions out of engagement with the racks during the forward stroke of the shaft and in such engagement during the rearward stroke of the same shaft, in combination with means operated from a key whereby the pinions are restrained from such engagement during the entire stroke of the main shaft.

In testimony whereof I affix my signature in presence of two witnesses.

CHARLES N. MCFARLAND.
